Primary Examiner—Bernard Ansher*Assistant Examiner*—R. Barkai*Attorney, Agent, or Firm*—F. A. Sirr; E. C. Hancock[57] **CLAIM**

The ornamental design for a hand grip for an in-line roller skate brake actuator, as shown and described.

DESCRIPTION

FIG. 1 is a front, top and right side perspective view of a hand grip for a roller blade brake actuator showing our new design and showing the hand actuator thereof in a depressed and locked position;

FIG. 2 is a front, top and left side perspective view thereof showing the hand actuator in a released and unlocked position;

FIG. 3 is a right side plan view thereof;

FIG. 4 is a left side plan view thereof;

FIG. 5 is a front plan view thereof showing the hand actuator in the depressed and locked position;

FIG. 6 is a rear plan view thereof showing the hand actuator in the released and unlocked position;

FIG. 7 is a bottom plan view thereof showing the hand actuator in the depressed and locked position; and,

FIG. 8 is a top plan view thereof showing the hand actuator in the released and unlocked position.

FIG. 1

FIG. 2

FIG. 7

FIG. 8

FIG. 3

FIG. 4

FIG. 5

FIG. 6
